[57] CLAIM

The ornamental design for a portable laser scanner, as
shown and described.

DESCRIPTION

FIG. 1 is a perspective view of a portable laser scanner
showing my new design;

FIG. 2 is an enlarged side elevational view thereof, the
opposite side elevational view being a mirror image;

FIG. 3 is an enlarged top plan view thereof;

FIG. 4 is an enlarged bottom plan view thereof;

FIG. 5 is an enlarged front elevational view thereof;

FIG. 6 is an enlarged rear elevational view thereof.

FIG. 1

FIG. 2

FIG. 3

FIG. 5

FIG. 6

FIG. 4
